CONTROL FOR SUPERCHARGERS

Rolf Ammann, Munich, Germany, assignor to
 Bayerische Motoren Werke Aktiengesellschaft,
 Munich, Germany, a company of Germany

Application February 17, 1939, Serial No. 256,886
 In Germany June 9, 1937

6 Claims. (Cl. 230—114)

This invention relates to an improved control for superchargers, and more particularly to a correlated throttle valve and speed control system for the same.

5 An object of this invention is to provide an improved supercharger control arrangement particularly adapted for use with aircraft engines.

10 A further object of this invention is to provide an improved control arrangement for properly correlating the action of a supercharger throttle valve and the supercharger speed control gearing.

15 An additional object of this invention is to provide an arrangement for interconnecting the throttle valve and speed change control of a supercharger in such a manner that undesired speed changes in response to control movement of the throttle valve are avoided.

These and other features, capabilities and advantages of the invention will appear from the 20 subjoined detailed description of one embodiment and modification thereof, illustrated in the accompanying drawings, in which:

Fig. 1 is a partially schematic view illustrating 25 a preferred control arrangement for the throttle valve and transmission of an engine supercharger; and

Fig. 2 illustrates a modified linkage system interconnecting the throttle valve and supercharger 30 drive.

In the preferred arrangement illustrated in Fig. 1, a throttle valve 1, in the form of a butterfly valve, is controlled by a pressure-responsive device generally indicated at 2 and a hand lever 3 for varying the amount of air supplied to the 35 supercharger 4. Assuming that the supercharger 4 supplies air to an aeroplane engine, the hand lever 3 is positioned adjacent the operator of the aeroplane for varying at will the position of the throttle valve 1 and/or the setting of the pressure-responsive device 2. The latter is preferably interconnected by a suitable conduit 5 with the discharge side of the supercharger 4, whereby, 40 by a variation in the discharge pressure, which, in turn, will vary with the altitude of the aeroplane, acts upon the pressure-responsive device. The pressure-responsive element itself may take the form of a metal bellows 6 actuating a control 45 lever 7, which, depending upon the expansion or contraction of the bellows 6 will force oil under pressure to one side or the other of the piston 8. Movement of the piston 8 is transmitted to the throttle valve 1 through suitable links 9. As 50 previously stated, the hand lever 3 may be used to directly move the throttle valve 1, as by direct connection with one of the links 9, and also to predetermine the initial setting and response of the metal bellows 6, as through an interconnecting two-arm lever 10.

A two-speed drive, generally indicated at 11 is used to interconnect the supercharger 4 with the aeroplane engine (not shown). In the preferred form of this invention, illustrated in Fig. 1, the linkage system for controlling the transmission 5 11 from the throttle valve 1 preferably consists, as shown, of a first double-arm lever 12, pivoted intermediate its end about a fixed point, a link 13 pivotally interconnecting one end of this first double-arm lever 12 with one end of a second 10 double-arm lever 14 also pivotally mounted intermediate its ends about a fixed point. The other end of the double-arm lever 14 is then suitably interconnected with the throttle valve 1 through links 15. The other end 16 of the double-arm lever 12 is preferably interconnected through a tension spring 17 with one end of an arm 18 pivoted suitably about fixed point 19. Actual switching of the transmission from one step to the other is accomplished through a link 20 20 which is pivotally interconnected to the free end of the arm 18 and actuates a gear control lever 21. By a suitable dimensioning and arrangement of this linkage system, as has been shown in Fig. 1, it will be seen that intermediate the end positions of the valve 1, that is, intermediate the full open and full closed positions, the valve 1 together with link 15, double-arm lever 14, link 13, and double-arm lever 12 may move relatively freely, being affected solely by the spring 17 25 which will act as substantially a fixed point for the arms 20 and 21 of the transmission. However, assuming that the valve 1 reaches its full open position, indicated by the dashed lines, the end 16 of the double-arm lever 12 will have 30 moved to the other side of the pivot point 19, acting as a dead center, and the spring 17 will quickly assume substantially the same relative position on the other side of the point 19. Through the links 20 and 21 such movement of 35 the spring and the free end of the arm 18 will effectively instantaneously shift the transmission 40 45 50 55 60 65 70 75 80 85 90 95 100 105 110 115 the dead-center point 19, thereby actuating link 20 and control lever 21 to move the transmission 11 to a higher speed for the supercharger 4. Increased air will then be supplied to the engine, although the air supply to the supercharger 4 itself will immediately become throttled to some degree through movement of the pressure-responsive device in accordance with the increased outlet pressure of the supercharger. This slight reverse movement, however, can take place without reversal of the gear drive to the lower step because of the resilient connection between the double-arm lever 12 and the pivoted arm 18. As the aeroplane ascends to still further heights, the valve 1 will again open until at the maximum rated height the supercharger will be supplied with its maximum of air and will be running at its maximum speed. As the aeroplane descends, the arrangement will work in an identically opposite sequential manner, as will be obvious to those skilled in this art without further discussion.

In the modification illustrated in Fig. 2, the necessary lost motion between the double-arm lever 12 and the transmission controls 20, 21 is effected by an alternative arrangement. In this case, a slotted guide 22 is provided on the free end of a link 23 pivoted to the lower end of the double-arm lever 12. About a substantially fixed point 24 there is pivoted intermediate its end another double-arm lever 25 provided at one end with a pin 26 engaging the slotted guide 22, and at its other end pivotally interconnected to the link 20 actuating the transmission control lever 21. It will be seen that this arrangement works in a manner similar to that previously described and illustrated in Fig. 1. A certain amount of movement of the double-arm lever 12, resulting from intermediate movement of the valve 1, will be permitted, since the slotted guide 22 will merely slide on the pin 26. When, however, the valve 1 reaches its end position, the double-arm lever 12 will have moved to such a degree that the end of the slotted guide 22, coming into contact with the pin 26 will rotate the double arm lever 25 to a position in which the transmission, through link 20 and control lever 21 will have been moved to another driving step. In the new position, indicated by the dashed line in Fig. 2, the throttle valve may be closed to some degree without reversely moving the gear of the supercharger drive. Upon descent of the aeroplane, however, a reverse shifting of the supercharger drive will take place as the pin 26 will then be moved by the opposite end of the slotted guide 22.

It will be obvious to those skilled in this art that other variations and modifications of the aforescribed arrangement may take place, all within the scope of the present invention. For example, the specific type of pressure-responsive device illustrated is of no particular importance, and any proper device, some of which are well known in the art, may be used to initiate the control. Additionally, if desired, the pressure-responsive actuating device may be responsive to atmospheric pressure directly, if so desired. While the control of the speed-change drive 11 has been indicated as a direct one, the interconnecting link 20 might easily act upon suitable indirect gear shifting mechanism of the type well known to the art. Additionally, while the linkage

system or shifting the speed-change drive has been illustrated as directly interconnected with the valve 1, it will also be obvious that it might, with substantially the same results, be directly connected to the pressure-responsive device. In this case, the linkage mechanism is so arranged that in case of complete opening of the pressure-responsive regulator the switching from the lower to the higher steps will take place, and upon complete closing, switching back from the higher to the lower step will follow.

I claim:

1. In an arrangement adapted for use with an internal combustion engine, in combination, a supercharger for said engine, a two-speed transmission drivably interconnecting said engine and said supercharger, a control lever for actuating said transmission to one or the other of said speeds, means for controlling the supply of air to said supercharger including a throttle valve movable between extreme opened and closed positions, pressure-responsive means for controlling said throttle valve, and linkage means directly interconnecting said throttle valve and said control lever for changing the transmission from one to the other speed only when said throttle valve reaches substantially either one of its extreme positions.

2. The combination according to claim 1, in combination with manual means for actuating said throttle valve and controlling the initial set of said pressure-responsive means.

3. The combination according to claim 1, in which the means interconnecting said throttle valve and said control lever includes a lost-motion device for permitting movement of said throttle valve between its extreme positions without initiating actuation of said transmission.

4. The combination according to claim 1, in which the means interconnecting said throttle valve and said control lever include means for urging said transmission to one or the other speed while permitting movement of said throttle valve intermediate its extreme control positions.

5. The combination according to claim 1, in which the means interconnecting said throttle valve and said control lever include an arm pivotally fixed at one end, a control rod connected at one end to said control lever and pivotally connected at its other end to the other end of said arm, a double-arm lever pivotally fixed intermediate its ends, a linkage pivotally interconnecting one end of said double-arm lever to said throttle valve, and a spring interconnecting the other end of said double-arm lever with the other end of said arm.

6. The combination according to claim 1, in which the means interconnecting said throttle valve and said control lever includes a pair of double-arm levers pivotally fixed intermediate their ends, a first control link pivotally interconnecting one end of one of said arms to said control lever, a second control linkage pivotally interconnecting one end of the other of said double-arm levers to said throttle valve, and a connecting rod pivotally connected at one end to the other end of the other of said double arm levers and provided with a slotted guide engaging the other end of said one double-arm lever.
